W. H. G. GEAKE

DRAFT EXCLUDER

Filed Aug. 12. 1924

FIG. 1.

FIG. 2.

FIG. 3.

FIG. 4.

FIG. 5.

Inventor
William H. G. Geake,
by Attorney.

UNITED STATES PATENT OFFICE.

WILLIAM HENRY GREGORY GEAKE, OF KILLARA, NEAR SYDNEY, NEW SOUTH WALES,
AUSTRALIA.

DRAFT EXCLUDER.

Application filed August 12, 1924. Serial No. 731,638.

To all whom it may concern:

Be it known that I, WILLIAM HENRY GREGORY GEAKE, a subject of the King of Great Britain, residing at Killara, near Sydney, in the State of New South Wales, Commonwealth of Australia, have invented certain new and useful Improvements in Draft Excluders, of which the following is a specification.

10 This invention relates to improvements in draft excluders for doors or the like, of the type comprising a strip of wood, metal, and other suitable material adapted to be movably attached to a door or casement window adjacent the lower edge of the latter and which is lowered to or raised from the floor or the bottom lintel when end pressure is imparted to the strip against the action of springs, when the door or window is closed 20 and released when the door or window is opened.

My object has been to provide a draft excluder of this character which may be sold as an article of manufacture and which is 25 capable of being readily fixed in position by any unskilled person and in which the strip is always in contact with the door or window so that no space is left between for ingress of air; wherein the springs for raising the 30 strip may be practically enclosed; in which guide slots are dispensed with; and in which the descent or ascent of the strip is accelerated towards the final or initial stage respectively. A further object of the invention is to provide an article of the character 35 referred to which may be applied to either a right or left hand opening door, as the case may be.

The invention will be described with reference to the accompanying drawings in which is illustrated a practical embodiment thereof.

Figure 1 is a front elevation of the lower portion of a door having a draft excluder 45 which embodies a preferred form of the invention fitted thereto, the draft excluder being shown in the raised position.

Figures 2 and 3 are partial side elevations on an enlarged scale showing a portion of my draft excluder secured to a door, the strip being shown in the raised and lowered 50 positions respectively.

Figure 4 is a perspective view of one of the springs, and

Figure 5 is a sectional view, on an enlarged scale on line 5—5, Figure 1.

The same numerals indicate the same or corresponding parts.

8 is a strip of wood or other suitable material provided with slots or recesses 9 in which are secured diagonally positioned pins 10 which are associated with a spring, hereinafter referred to. These pins are inclined at an angle of about 70° to the lower edge of the strip and, whilst tending to minimize friction with their associated springs, insure quick descent of the strip. 11 is a spring provided at or adjacent one of its ends with a pair of aligned eyes or loops 12 through which is passed a nail or screw 13 to secure the device to a door or window, the position of the eyes being such that the correct placing of the screws is facilitated. A U-shape portion 17 is formed in the spring between the eyes 12. A further loop 14 is formed in the spring 11 about midway of its length to increase the resiliency of the spring. A suitable rubber or felt edging 15 may be secured to the lower edge of the strip 8.

16 represents a door to which the device is shown as attached.

To attach the strip 8 to a door 16 or window, the strip 8 is so placed at the lower edge of the door or window that one end slightly projects beyond the hinged edge of the door or window, and a nail or screw 13 is passed through the respective eyes or loops 12 and secured to the door or window.

Assuming that the door or window to which the device is attached to be open, the parts will be in the position shown in Fig.

2. Where the door or window is closed, the projecting end of the strip 8 contacts with the jamb of the door or the window casement and the strip 8 is thus shifted toward the opposite edge of the door. That end wall of each of the slots or recesses 9 which is nearest the hinged edge of the door will thus be caused to press against the rear end of its spring 11, and, since the opposite end of each of said springs is secured to the door by its screw 13, the latter end of the spring can only rock on said screw. The pins 10 will, therefore, be caused to ride downwardly between the U-shaped portions 17 of the springs and the screws or nails 13, thus causing the strip 8 to move downwardly 100 quickly and to contact closely with the floor

100

105

to exclude any dust or draft under the lower edge of the door 16.

When the door or window is opened the rear ends of the springs 11 bearing against the rear ends of the slots or recesses 9 will shift the strip 8 in the opposite direction, thus causing the pins 10 to move upwardly through the U-shaped portion 17 of the spring and the screw or nail 13. It will be noted that, since the U-shaped portion 17 of the springs straddles the pins 10, and since the eyes 12 at the ends of said U-shaped portion 17 are secured to the door by the screws or nails 13, said screws or nails also serve to secure the strip 8 to the door, and that the strip may be removed from the door by simply removing the screws or nails 13. Instead of forming a U-shaped portion 17 on the spring 11 between the eyes 12 to slide on the pin 10, I may form a loop between said eyes, in which case, it is necessary to remove the pin 10 before withdrawing the spring 11.

The slots or recesses 9 may have cover plates to prevent ingress of dust.

25 It is obvious that I may use more than two slots or recesses each fitted with a diagonal pin. The slots, however, must be so spaced that the strip will always be parallel to the floor.

30 I claim.

1. A strip for attachment to a door adjacent the lower edge of the latter with one end in engagement with the door jamb at the hinged edge of the door, said strip having a slot extending therethrough, a spring contained in said slot with one end in engagement with a wall of said slot and tending to move said strip toward the hinged edge of the door, said spring having means 35 to receive a hold-fast device for securing said spring and said strip to the door, and means mounted in said slot and associated with said spring and adapted to cause said strip to move beyond the lower edge of the door when the end of said strip bears against the door jamb during the closing movement 40 of the door.

2. A draft excluder for doors or the like comprising a strip for attachment to a door adjacent the lower edge of the latter with its lower edge adapted to project beyond the lower edge of the door and one of its ends adapted to project beyond the hinged edge 45

of the door, said strip having a slot therethrough, a spring in said recess having one 55 of its ends engaging one wall of said recess and tending to move said strip longitudinally toward the hinged edge of the door and having its other end formed with a pair of aligned eyes to receive a hold-fast device 60 for securing said spring and said strip to a door and with a loop between said eyes, and a pin extending diagonally of said slot between the loop and eyes of said spring, said pin adapted by engagement with said loop 65 and with the hold-fast device extending through said eyes to cause the lower edge of said strip to move beyond the lower edge of the door when the strip is shifted longitudinally by engagement of its end with the 70 door jamb during the closing movement of the door and to cause the lower edge of said strip to rise when the strip is shifted longitudinally in the opposite direction by said spring during the opening movement of the 75 door.

3. A draft excluder for doors or the like comprising a strip for attachment to a door with one end in engagement with the door-jamb at the hinged edge of the door and having its lower edge movable beyond the lower edge of the door, said strip having a plurality of slots therethrough, a spring in each of said slots having one of its ends in engagement with one end of its slot and tending to shift said strip toward the hinged edge of the door, said spring having means 80 at its other end to receive a hold-fast device for securing said spring and said strip to the door, and means extending transversely of said slot at an inclination to the lower wall of the latter for engagement with said hold-fast device, said means adapted by its engagement with said hold-fast device to cause said strip to rise from the lower edge of the 85 door when said strip is shifted longitudinally in one direction by said spring during the opening movement of the door and to cause the lower edge of said strip to project beyond the lower edge of the door when 90 said strip is shifted longitudinally in the opposite direction by engagement of the end thereof with the door jamb during the closing movement of the door.

WILLIAM HENRY GREGORY GEAKE.
